(57) **CLAIM**

The ornamental design for a valve collar lock, as shown and described.

DESCRIPTION

FIG. 1 is a right side perspective view of a valve collar lock showing my new design;
FIG. 2 is a left side perspective view thereof;
FIG. 3 is a front elevational view thereof;
FIG. 4 is a rear elevational view thereof;
FIG. 5 is a right side elevational view thereof;
FIG. 6 is a left side elevational view thereof;
FIG. 7 is a top plan view thereof;
FIG. 8 is a bottom view thereof; and,
FIG. 9 is a perspective view of the valve collar lock shown assembled and in an environment of use.
The broken lines showing a valve in FIG. 9 illustrate environmental structure and form no part of the claimed design.
The valve collar lock is shown with a symbolic break in its length. The appearance of any portion of the article between the break lines, as well as the break lines themselves, form no part of the claimed design.
